PERFORATING AND STAINING
MECHANISM

Harry Cohen, New York, N. Y.

Application February 11, 1933, Serial No. 656,243

10 Claims. (Cl. 101—26)

This invention has reference to the art of duplicating instruments, and particularly relates to a perforating and staining needle or instrument capable of simultaneously penetrating and staining several layers of material for duplicating purposes.

Among the objects of my invention may be noted the following: to provide a needle or instrument so constructed as to enable it to penetrate a plurality of thicknesses of material, such as paper or fabric, and at the same time to stain the material surrounding the line of penetration; to provide a device of the kind stated which can be used to duplicate patterns and correct mis-takes and inaccuracies made while producing the same; to provide a perforating device with means enabling it to be power driven and with means enabling it to mark several layers of material in one or more colors; to provide a duplex perforating and staining implement which can be motor-driven and the driving means can be caused to operate upon placing the instrument in position for a functional purpose; to provide a perforating and staining implement capable of being driven by power, and the implement and its power means capable of being freely adjusted and manipulated relatively to the work, and the power means set in operation when the executive end of the implement is caused to engage the work and thrown out of operation when the implement is removed from the work; and to provide details of construction enabling the implement to operate and function as stated in the foregoing.

With the above objects in view and others which will be detailed during the course of this description, my invention consists in the parts, features, elements and combinations thereof hereinafter described and claimed.

In order that my invention may be readily understood, I have provided drawings wherein:

Figure 1 is a view showing my duplex perforating and staining implement in side elevation, the same including power means for actuating the two perforating and staining devices or instruments;

Figure 2 is a view in front elevation of the executive end of one portion of the implement, showing details of the guiding and pressure means;

Figure 3 is a bottom plan view of the parts shown in Figure 2;

Figure 4 is a view in sectional elevation, enlarged, of the lower portion of my implement;

Figure 5 is a cross-sectional view of my device on the line 5—5 of Figure 4;

Figure 6 is a similar view on the line 6—6 of Figure 4; and

Figure 7 is a similar view on the line 7—7 of Figure 4.

Referring to the drawings and particularly to Figure 1, the numeral 1 indicates a guide wire faultily strung in any convenient place and manner. A trolley 2 is guided on said wire, and pendant therefrom are flexible supporting wires 3 to which a suitable motor is secured. The motor is housed in a frame 4 having a cylindrical hand-hold 5, terminating in a supporting cover 6, operating as a cap or shield for the main perforating device 7 and auxiliary perforating device 8. These devices 7 and 8 are each composed of a sheath of tubular, drawn or stamped and soldered or brazed metal, uniform in diameter to near the lower end, which is formed tapering, as at 9. The lower end of each sheath is truncated, and the said tubular members each contain the executive elements thereof. The main device, midway the length of its sheath 7, is provided with a diagonally disposed gripping medium 10 adapted to receive the thumb of the user, while the fingers, one or more, extend around the device 8, sufficiently, as at 11, to enable the entire implement to be readily handled. The lower end of each sheath has a lug 12 secured thereto in which one end of a lever 13 is pivoted and which extends across the lower end of the sheath and has a guiding member 14 at its outer end adapted to receive the edge of a pattern 15 to thus properly direct the implement, as presently described,—see Figures 1 to 4. Between its ends the lever 13 is provided with a curved portion 16 which extends around the longitudinal center of the sheath, thus avoiding contact with the perforating and staining device. At the outer end of the curved portion 16 of the lever 13, a stiff wire or rod 17 is pivotally connected, said wire extending lengthwise of and within the sheath, through the cap 6, and the hand-hold 5, and outside the motor-casing 4, whereon it is pivotally connected to one end of a switch 18 pivoted to the casing 4, between two contacts 19 and 20 so as to close the circuit and convey the current to either side or member of the duplex implement. Normally, the lever 13 is depressed, as at the left-hand side of Figures 1 and 4, so as to open the switch 18, by means of a flexible spring 21, secured to the bottom of the sheath and resting upon the top of lever 13 between the wire 17 and the guide 14. The lower end of the sheath is also provided with a pressure roller 22 journaled on a bracket 23 fixed to the sheath. The roller parallels the guide so as to press against the body of the pattern within its edge, as shown in Figures 1 to 3, thus giving the implement anti-frictional contact while in operation and relieving the hand of strain.

As shown in Figures 4 to 7, inclusive, a plurality of lugs 24 are spaced equidistantly about the interior of the sheath 7, the same being adapted to support coiled springs 25, the upper ends of

which rest against lugs 26 carried by the lower end of the needle shank. The sheath 7 is also provided with oppositely disposed longitudinal splines 27 adapted to enter grooves between webs 28 secured to the exterior of the needle shank. The springs support the needle in its normal raised position out of contact with the material 15, and the splines and grooves prevent the needle from turning or twisting within the sheath 7 during the operation of the needle, and also hold the needle centrally within the sheath and so as to operate within the bend 16 of the presser-foot. The needle consists of the tubular shank 29 which is contained loosely within the sheath, there being ample space between the two to enable the wire 17 to pass between the walls thereof and outwardly into cap and hand-hold and into engagement with the switch lever 18. The outer end of the needle shank is composed of a rounded solid portion 30, and the inner end of said shank is provided with a nipple 31 internally threaded to receive the externally threaded outer end of the needle body and reservoir 32. The needle body is hollow throughout its length and is tapered, as shown in Figure 4, and the chamber thereof communicates through the narrow passage 33 with the chamber of the shank 29. The passage 33 is through the head of the nipple 31 and an elongated tubular teat 34, said teat being adapted to receive the lower end of the flexible tube 35 of the bag 36 adapted to contain the staining liquid. The outer end of the bag is provided with a short, flexible neck 37 which passes through a slot 38 in the shank of the needle and is threaded, as at 39, into the sheath and into a nut-like closure 40 for the said bag. The nut 40 and a shoulder 41 on the neck 37 tightly clamp the bag in position within the needle shank 29 and hold it normally as shown in Figure 4. The executive end of the needle, as shown in Figure 4, is formed into a penetrating point 42 above which are placed circumferentially of the tubular portion a plurality of apertures 43 extended into shallow grooves 44. The apertures enable the liquid in the needle to seep from the chamber of the latter, and the grooves hold a minute portion of the liquid insuring proper staining of the material during the reciprocation of the needle. The head 30 of the sheath is engaged by an eccentric 45 adapted to operate upon the solid head 30 of the shank 29, said eccentric being carried by the stud-shaft 46, which is adapted to slide in the open-end groove 47 at the upper end of the sheath. The shaft 46 also carries adjacent the eccentric, but spaced therefrom, a bevel pinion 48 which meshes with a bevel pinion 49 carried on the free end of the flexible driving shaft 50 extending from the motor, as shown in Figures 1 and 4.

As previously suggested, the duplex character of the implement is carried out by giving the portion 8 thereof all the structural and characteristic features of the portion 7; and the two portions 7 and 8 are held in proper and intimate relation by the elongated, angular tongue 51 carried by the sheath 8, and the correspondingly elongated grooved, angular member 52 carried by the sheath 7. The tongue 51, while fitting in the groove snugly, may readily be shifted therein so as to enable the sheath 8 to be normally held with its guide and roller out of contact with the work as shown in Figures 1 and 4. The bag, not shown, of the portion 8 of the duplex instrument, is adapted to carry a fluid of different color from that of the bag 36 of the portion 7; that is to say, the bag of the portion 7 may carry green ink or fluid, while the bag of the portion 8 may carry red ink or fluid. An open-end groove 47^a is provided near the upper end of the sheath 8, and this groove is adapted to register with the groove 47 in the sheath 7 so that, when the sheath 8 is shifted outwardly in the cap 6 to functional position, the stud-shaft 46 and the driving mechanism carried thereby may be shifted from sheath 7 to sheath 8 so that the eccentric 45 may operate upon the solid head of the needle shank within the sheath 8. As shown in Figures 1, 4 and 5, each of the sheaths 7 and 8 is provided with a latch 53 held in either of two positions by thumb nut 54, the said latch being adapted to be shifted circularly into engagement with one headed end 55 of the stud-shaft 46 which carries the eccentric and bevel gear. The functional position of the latch is shown in Figure 5, while the inoperative position of the latch is shown in Figure 4. Thus, regardless of the portion of the duplex implement which is in operation, the needle actuating mechanism may be held properly in the groove 47 and 47^a, in position to accurately centrally engage the solid head of the needle shank.

From the foregoing description of the details of construction, the following mode of operation will be readily understood. Normally, the driving mechanism, including the eccentric 45, will be held in the slot 47 so that the eccentric can actuate the needle in the portion 7 of the implement, the portion 8 of the implement being elevated out of functional position as shown in Figures 1 and 4. Normally, the portion 7 of the implement will be utilized because it is necessary that the green ink, for example, shall be the main coloration of the duplicated patterns, the red ink of the portion 8 of the implement being intended to indicate corrections only, the portion 8 consequently being utilized only semi-occasionally when mistakes have been found and corrections are to be made. The implement, with the parts in the position of Figure 1, is held in the hand with the thumb seated in the grooved member 10, and the fingers extending around the two portions 7 and 8, as indicated at 11, the operator thus being able to hold the two portions 7 and 8 in proper operative relation at all times and steadily for manipulation as required. The trolley 2 is mounted on the guide-wire 1 and by gripping the hand-hold 5 the entire implement can be shifted quickly and easily to approximately the position desired for beginning the work. The current wire or connection to the motor (not shown) will be extended in any direction desired to plug in for power. The patterns 15 being made of suitable material, and it being desired to produce therefrom an indefinite number of duplicates, as from the material piled as shown at 56, Figure 4, on the table or support 57, the implement is gripped as explained, and its executive end is lowered so that the guide 14, of portions 7, will engage the edge of the pattern 15 and the pressure roller 22 will engage the body of the pattern back of its guiding edge. Thus positioned, the needle of the implement will be enabled to penetrate the materials 56 below and beyond the edge of the pattern 15; and as the implement is pressed downwardly upon the pattern 15, the lever is caused to actuate the wire or rod 17 and thus shift vertically the switch lever 18 into engagement with either contact 19, or contact 20, according to the portion of the implement utilized. Normally, the operation will begin with the use of the portion 7 of the implement and as the needle is forced

downwardly will penetrate the various thicknesses of material 56, and the liquid in the needle will flow therefrom through the apertures 43 and into the grooves 44 and by capillary attraction will be

5 retained by the materials and saturate the same a short distance surrounding the needle penetration. This normal operation will continue until, for some reason, it is desired to utilize the portion 8 with the red ink or fluid, as when a mistake is
 10 discovered in the reproduction of the pattern 15, whereupon the operator will lift the implement from the work, thus enabling the spring 21 to depress the guide-lever 13 downwardly which will shift the switch 18 downwardly and break contact at 19. Now the latch 53 is released and turned downwardly out of the way so as to release the stud-shaft 46 carrying the cam 45. The portion or sheath 8 of the implement will now be depressed so that it may be slid downwardly on
 15 the sheath 7 so as to cause the slots 47 and 47^a to register. The stud-shaft 46 will now be shifted over from the slot 47 into the slot 47^a of the sheath 8, whereupon the latch 53 of the latter will be turned upwardly into contact with the head 55 of
 20 the stud-shaft 46, thus holding the latter in the proper position for engagement with the head 30 of the needle shank 29. Then the portion 8 of the implement will be still further shifted relatively to the portion 7, so that the executive end 25 of its needle and the guide and pressure roller may be caused to extend beyond the portion 7, and to engage the work as desired independently of the portion 7, the latter now being out of operative position.

30 Pressure, by the operator, upon the implement will cause the guide and roller to engage the pattern-edge and surface, respectively, and as the guide-lever 13 rises, its connected switch-rod 17 will shift the switch 18 into engagement with contact 20, whereupon the motor will cause the cam 45 to actuate the needle of portion 8. This will continue until it is desired to again use the instrument 7, whereupon the instrument 8 will be rendered inoperative, the cam 45 shifted over and fastened to instrument 7, whereupon the latter will be again ready for operation, all as will be readily understood from the foregoing description.

Having thus described my invention, what I claim and desire to secure by Letters Patent is:

50 1. A duplicating implement comprising a pair of perforating and staining devices shiftably connected together, and means whereby at will one or the other of said devices can be utilized.

55 2. A duplicating implement consisting of a pair of perforating and staining devices slidably connected together, means for coupling the same, and means whereby one or the other of the devices can be caused to function.

60 3. A two-color perforating and staining implement consisting of two like members slidably connected together, a perforating and staining device carried by each of the members, a guide carried by each of the members forming said connection, and means whereby one or the other of said devices may be actuated so as to utilize at will either of the devices.

65 4. A duplex perforating and staining implement comprising two like portions, each of which consists of a sheath, means coupling the two portions slidably together, each of said portions being pro-

vided with a perforating and staining instrument, and power means whereby either of said instruments may be activated according to functional requirements.

5. A duplex perforating and staining mechanism consisting of a plurality of casings, means for coupling the two slidably so that one or the other of the casings may be shifted to functional position, each of said casings being provided with a combined perforating and staining instrument operating through one end of its casing, and power actuating means coupled with the mechanism for actuating either one or the other of the perforating instruments.

80 6. A duplex perforating and staining implement consisting of two like parts, each carrying a combined perforating and staining instrument, means for slidably coupling the two parts together so that one may be shifted relatively to the other, a single activating means for each of the said instruments, the said two like parts being provided with means whereby when the one is shifted on the other the activating means may be shifted from one to the other, thus enabling either one of the combined perforating and staining instruments to be activated for functional purposes.

85 7. In combination, an electric motor, a combined perforating and staining implement, electrical means coupling the motor with the implement for actuating its perforating and staining instrument, guiding means for the implement, and a connection between the guiding means and the motor for causing the current from said coupling to drive the instrument when the implement is engaged with the work.

90 8. In combination with a suitable supporting means, a driving motor suspended thereon for universal movement relatively thereto, a perforating and staining instrument, means between the said instrument and the motor whereby the two may be manipulated together upon said support, means carried by the instrument for engaging the work, and means connecting the engaging means with the motor whereby, when the engaging means contacts the work, the motor may be thrown into operation to actuate the instrument.

95 9. A perforating and staining mechanism having a pair of needles arranged side-by-side and adapted to perform their functions alternately, driving means for positively actuating the two needles, and means whereby the driving means may be shifted from one needle to the other as desired and according to the needle to be actuated.

100 10. A combined perforating and staining implement consisting of a sheath having a cap for closing one end thereof, the other end being open, a combined perforating and staining instrument mounted and freely sliding within the sheath and having an apertured point adapted to pass through the open end of the sheath, power actuated means within the cap for activating the instrument by loosely engaging the adjacent end thereof, guiding and pressure means at the open end of the sheath and mounted on the latter for engaging the work, and the power means being connected by mechanical means with the guiding means whereby the power actuated means may be brought into action.

HARRY COHEN. 145
